CLAIM

(57) The ornamental design for a helmet display holder for a cord, as shown and described.

DESCRIPTION

FIG. 1 is a perspective view of a helmet display holder for a cord of the present invention;

FIG. 2 is a front elevational view of the helmet display holder for a cord of FIG. 1;

FIG. 3 is a rear elevational view of the helmet display holder for a cord of FIG. 1;

FIG. 4 is a left side elevational view of the helmet display holder for a cord of FIG. 1;

FIG. 5 is a right side elevational view of the helmet display holder for a cord of FIG. 1;

FIG. 6 is a top elevational view of the helmet display holder for a cord of FIG. 1; and,

FIG. 7 is a bottom elevational view of the helmet display holder for a cord of FIG. 1.
